UNITED STATES PATENT OFFICE

HENRY M. KANNEE, OF NEW YORK, N. Y.

AUTOMATIC DRYING DEVICE FOR INKED SHEETS

Application filed June 5, 1930. Serial No. 459,816.

The object of the present invention is to provide a device which will receive freshly inked sheets from a printing, lithograph, stencil or other ink applying device and which will permit the sheets to descend by gravity in the form of a plurality of superposed and spaced sheets until one by one they fall to a delivery point which may be a tray. The characteristic of the device is that the sheets have a gravitational movement from an upper point to a lower point and in such movement are given sufficient time for the ink to set, so that when the sheets are finally deposited one in contact with the other the ink will not blur or offset on the reverse side of the succeeding sheet. A further object of the invention is to provide a device of this character which shall be simply constructed, and capable of operation for long periods without derangement.

The invention will be described with reference to the drawings in which

Fig. 1 is a view in side elevation of an embodiment, with a side plate broken away, the device being applied to a type of stencil machine so as to be driven from the driving means of the latter.

Fig. 2 is a plan view of the device.

Fig. 3 is a horizontal section on the line 3—3, Fig. 1.

Fig. 4 is an enlarged view in elevation of the spiral plates and bladshafts.

Fig. 5 is a fragmentary and enlarged vertical section on the line 5—5, Fig. 2.

Fig. 6 is an enlarged section on the line 6—6, Fig. 1.

Fig. 7 is a fragmentary elevation of the blade-shaft.

Fig. 8 is a diagrammatic view showing a method of assembling the blades by overlapping their edges.

Referring to the drawings, I have therein shown a rectangular frame comprising lower horizontal frame members 1, of tubing, connected at their ends by elbow joints 2, each joint having an upwardly extending sleeve-like member 2 α , to receive a vertical frame member 3. Vertical frame members 3 at the top of the frame are received within depending sleeves of four elbow connecting

members 4 which members 4 receive the four tube-like upper horizontal frame members 5. Held by opposed sets of sleeves 6 on lower frame members 1 are cross frame members 7. Each frame member 7 has keyed thereon spaced sleeves 8, (Fig. 1) each sleeve having a vertical, recessed extension 8 α , affording a bearing seat for a blade-shaft 9. Keyed to each blade-shaft at the top of the vertical extension 8 α of sleeve member 8, is a pinion 10. The pinions are connected for simultaneous rotation by means of two inter-meshed idler pinions 11. These pinions are supported from cross frame members 12, each frame member 12 receiving a sleeve 13 (Fig. 1), the sleeve having a vertical, recessed extension adapted to receive a screw-stud 14 (Fig. 3), threaded into said vertical extension, such construction being well known in the mechanical arts, and not requiring detailed illustration or description.

The upper ends of three of the blade-shafts 9 are received within the lateral apertured extensions 15 α of sleeves 15 (Fig. 2) mounted upon cross frame members 17, which latter are at one end secured to one of the upper frame members 5 and which at the opposite end are bent upwardly and flattened at 17 α . These flattened ends are apertured so that they may be bolted to a bar 18, carried by the stencil machine A, when the device is particularly designed for such application.

The fourth of the shafts 9 is mounted in the manner shown in detail in Figs. 2 and 6. Carried by one of the upper frame members 5 is a bracket 19. Bracket 19 is also supported by shaft 17, a sleeve 19 α on the bracket receiving the latter shaft. Bracket 19 is formed with a vertical bearing-sleeve 20 which receives said fourth shaft 9 and the shaft carries a horizontal bevelled gear 21 in mesh with a bevelled gear 22 on a stub shaft 23. Stub shaft 23 is supported in spaced bearing bosses 24, and the shaft is provided with a sprocket wheel 25 which receives a chain 26, leading to a driven pulley 27 (Fig. 1) of the stencil machine A.

In the present embodiment each of the blade-shafts 9 is cut with a spiral groove 28 to receive a plurality of blades 29, the blades 100

being shown in plan view Fig. 2. Each blade is made as a disk cut from axis to periphery, and at one side of the cut gradually deflected, axially, until that portion of the blade at the opposite side of the cut lies, when the blade is horizontal, at a lower level, and exactly in register with the uppermost section of a lower blade to form a unit of a spiral. If the blades are made sufficiently stiff, and the edges are truly formed so that the upper edge of a blade will come into exact register with the lower edge of an upper blade, and the lower edge into register with the upper edge of a lower blade, the meeting edges of a plurality of blades may be held in abutment without brazing, welding, or other means of uniting them.

In Fig. 2, the blades are shown with arrows thereon indicating the direction of movement, and it will be seen that the blades have such direction that the paper fed thereon has a tendency to move to the rear of the device, or in other words in the direction of feed of the stencil machine, printing press, or other ink applying device.

At the top of the machine and suitably mounted, as for example, to the sleeve extensions 15^a, may be disposed opposed bars 30 which may support a rectangular frame, 30 of which a fragment is shown at 31 (Figs. 2, 5 and 6), the frame carrying a glass panel 32, through which the action of the machine may be observed from above.

In Fig. 1, I have indicated three successive positions of a sheet fed into the device by the stencil machine, the sheet being indicated at 6. The sheet is thrown forwardly by the feeding mechanism of the stencil machine A, the said movement of the sheet carrying it into the drying device, the forward and downward movement of the sheet carrying it into contact with the topmost blades. The rotation of the blades will be in synchronism with the feed of the stencil machine, as will be understood from the fact that driving pulley 27 of the stencil machine is directly connected by chain 26, with the driving mechanism of the drying device and the blade shafts are intergeared. The synchronism may be such that each sheet will fall upon the topmost blades when the upper edge of the spiral or first blade is in a position one-half revolution from that shown in Fig. 2 of the drawings. As the blades rotate in the direction of the arrows, the sheet will be caused to pass by gravity downward until it is finally dropped into the tray B.

I have discovered that it is unnecessary that the edges of one blade abut the lower edge of a top blade, and the upper edge of a bottom blade, inasmuch as the lower edge of one blade may slightly overlap the upper edge of an underlying blade throughout the assembly on a blade shaft, particularly when the blades are stamped out of relatively thin

sheet metal. In fact, this overlapping arrangement may serve of itself, as a method of separating the blades the required distance apart, although such means may be supplemented by washer-like spaces (not shown) 70 interposed between the blades, and surrounding the blade shaft.

What I claim is:

1. In drying devices for inked sheets, a plurality of sets of spaced vertical shafts, set 75 supporting means on each shaft, spiral in form, and adapted to permit gravitational movement of a set from an upper point to a lower point relatively to the shaft, the supporting means on one shaft of a set rotating within the peripheral point of rotation of the supporting means on a second shaft, and means for rotating the shafts in synchronism.

2. In drying devices for inked sheets, two sets of spaced vertical shafts, set supporting means on each shaft, spiral in form, and a sheet supporting means on the shaft of one set overlapping the same means on the second shaft of said set, a means for rotating the shafts in synchronism.

3. In drying devices for inked sheets, two sets of spaced vertical shafts, set supporting means on each shaft, spiral in form, and a sheet supporting means on the shaft of one set overlapping the same means on the second shaft of said set, a means for rotating the shafts in synchronism, the supporting means of one set of shafts being spaced from the sheet supporting means of the second set of shafts.

4. In drying devices for inked sheets, a plurality of spaced vertical shafts, means for rotating the shafts in synchronism, supporting means on each shaft comprising a plurality of disks, each disk being cut on an axial line from axis to periphery, the surface of the disk from one side of the cut being gradually deflected axially to the opposite side of the cut so that one margin of the cut lies at a point spaced from the margin of the other side of the cut, superposed disks overlapping along the margins of said cuts.

5. In drying devices for inked sheets, a plurality of spaced vertical shafts, sheet supporting means on each shaft comprising a plurality of disks, spiral in form, the shaft being formed with a spiral groove in which said disks are seated, and means for rotating the shafts in synchronism.

6. In drying devices for inked sheets, two tubular horizontal frame members, a vertical rectangular tubular frame member connecting said horizontal members and holding them in spaced relationship, cross frame members carried by the lower horizontal frame member, two sets of spaced pinions, two pinions in each set, carried by said cross frame members, idler gears connected to said pinions, a vertical shaft connected to each pinion, spiral sheet supporting means on 130

each shaft and adapted to permit gravitational movement of a sheet from an upper point to a lower point relatively to the shaft, cross frame members carried by the upper 5 horizontal frame member, bearing sleeves carried by the last named cross frame members and receiving the upper ends of said shafts, a drive shaft, and driving means intermediate said drive shaft and the upper end of one 10 of the vertical shafts, as and for the purpose described.

7. In drying devices for inked paper sheets, means for feeding sheets of paper edgewise and in succession, a plurality of opposed sets 15 of vertically disposed, helically spiral plate-like supports for gravitational feed of said sheets and means for rotating the supports in synchronism with the edgewise sheet feeding mechanism so that the sheets will successively 20 fall into position upon the sets of helically spiral supports when the topmost area of each support lies under a margin of a sheet said means rotating the supports of each set in opposite directions.

25 In testimony whereof, I have signed my name to this specification.

HENRY M. KANNEE.
